CIRCULAR KNITTING MACHINE

Application filed April 10, 1928, Serial No. 268,973, and in Great Britain April 23, 1927.

This invention comprises improvements in or relating to circular knitting machines and has for its main object to provide an improved mode of and means for producing 5 patterns and patterned effects by the selective displacement of thread guides.

An important feature of this invention consists in the employment in a circular knitting machine of jacquard mechanism for selectively operating the thread guides and determining the pattern to be produced in the fabric.

The invention has particular, although not exclusive, reference to that class of machine 15 wherein depending thread guides are disposed in a circular row or series around the machine and are directly or indirectly operated upon by a rotating cam device or the like so as to be displaced for laying their 20 threads on the needles.

Usually in connection with this type of machine the production of an all-round pattern, that is to say, a pattern extending the entire circumference of the fabric, is impossible by reason of the fact that the varying 25 of the pattern is dependent upon the rising and falling movement of the cam device co-acting with butts or projections on the guides or on members operating intermediate of said 30 cam and guides, and it is the customary practice to provide a section of the circumference of the machine devoid of the patterning thread guides, the cam being operated to be vertically adjusted when the position of the 35 cam coincides with the space devoid of such guides. In this way a vertical band of the fabric produced has no pattern therein, such band being in the case of stockings and socks usually located centrally at the back.

40 By the employment of the present invention an all-round pattern can be produced in the fabric, and an additional feature of the invention resides in the employment of jac- 45 quard mechanism either for actuating the whole of the circular series of patterning thread guides, or for operating upon a series or plurality of patterning thread guides pro- 50 vided in a machine of the above named type at that part which has usually been devoid of such guides.

Another feature of the invention consists in employing jacquard mechanism in a circular knitting machine in combination with a rotary cam device, said jacquard mechanism functioning selectively to displace 55 thread guides into a position in which they are unaffected by said cam device.

For the purpose of more fully describing the nature of this invention reference will now be made to the accompanying drawings, 60 wherein:—

Figure 1 is an elevational view, mainly in section, of a part of a circular knitting machine in accordance with one embodiment 65 of this invention.

Figure 2 is a similar view showing a modified form of the invention.

Figure 3 is a view of a jacquard device looking at the one side thereof.

Figure 4 is a view looking at the opposite 70 side of the same jacquard device.

Figure 5 illustrates a cam device suitable for operating two jacquard devices.

Figure 6 is a detail view showing the guide 75 operating cam coacting with a butt on the guide.

In one convenient method of carrying out the invention a circular row of dependent thread guides 1 are mounted at their upper ends upon a suitable stationary ring member 80 2 so that the lower ends of said guides are located approximately level with the hooks of the needles 3 when said needles are in the raised position, the guides being preferably of hook formation at their upper ends and 85 being so mounted as to be capable of a suitable degree of vertical displacement in addition to the radial or oscillatory movement necessary for moving the lower ends of the guides to a position exterior of the needles 90 for laying the threads.

Positioned centrally of the machine is a rotatable tubular spindle 50 carrying a suitable cam 5, advantageously in the form of a circular collar having a projecting cam bit on 95 its circumference. The tubular shaft or spindle 50 surrounds and turns about a stationary shaft 4. When the depending thread guides 1 are in the normal or operative position shown to the right in Fig. 1 this cam 100

5 is adapted during its rotary movement to coat with shoulders 1a formed on the guides by cranking or binding them, or with inwardly projecting butts 1b as shown in Figure 6, 5 or with butts formed on radially movable jacks located intermediate of said cam 5 and the guides, as represented in Fig. 2, the cam functioning to displace the guides (with or without jacks) radially outwards so as to 10 bring the patterning threads on to the front of the needles, a separate series of jacks 6 or their equivalent being adapted simultaneously to operate upon the lower parts of the guides to displace the latter laterally and lap or traverse the needles. 15

This lateral displacement of the thread guides is effected by shaping the jacks 6, which move radially, with intermediate bent or cranked portions that act upon the thread guides as the jacks 6 are moved outwardly, in a manner well known in this art. 20

In order to select certain of the guides for feeding their threads and maintain others of said guides inoperative jacquard mechanism 25 is provided, preferably located at the top of the machine a suitable distance above the upper ends of the guides. In the arrangement shown in Figure 1 wherein all of the guides in the circular row are adapted to be 30 operated by the jacquard mechanism, two jacquard devices are conveniently employed, one appertaining to one half and the other to the opposite half of the ring of guides and these being arranged to operate the said groups of 35 guides successively. Each jacquard device advantageously comprises one or more series of closely disposed horizontally slidable plate elements 7, one of which is provided in connection with each guide 1, each plate 7 having a depending arm 8 of crank formation pivoted at the angle of the crank to a fixed pivot 9, the lower approximately horizontal portion of said crank arm 8 being connected by a downwardly extending cord, wire or the like 10 to the upper end of the guide 1 to be 40 operated thereby. 45

These slidable plate elements 7 are guided in their movement by pins 11 at their rear ends engaging with perforations in a suitable 50 bar 12, and each plate has at its front end a pin 13 which is adapted to coat with an intermittently rotatable member 14 of square or other polygonal cross section over which passes an endless chain of jacquard cards 15, 55 said cards being maintained in position upon the rotatable member by suitable means.

The successive operation of the two jacquard mechanism devices is advantageously effected from any suitable drive shaft 60 Fig. 5 said shaft having thereon a cam member 17 with which is maintained in engagement a pair of cam trucks 18 each carried between the ends of an arm 19 extending substantially horizontally therefrom, each of 65 said arms being pivoted at one end to a part

of the machine frame and at its other end to the lower end of an upwardly extending rod 20, which rod is at its upper end connected through the crank arm 21 to a transverse spindle 21a on which are fixed a pair of further crank arms 21b having forked ends which coat with pins 22a carried by slidable rods 22 guided within bearings 23 and located one at each side of a frame or member 24 accommodating the aforesaid slidable jacquard plates 7. Each horizontally sliding rod 22 is suitably connected to the polygonal jacquard card carrier 14 and is reciprocated at intervals through the mechanism just described so as to move said carrier with the cards 15 into and out of engagement with the projecting pins 13 on the slidable plates 7. The operating devices associated with one jacquard device only are illustrated in Fig. 3, and it will be understood that such devices are duplicated in the other jacquard. 70 75 80

The jacquard cards are suitably punched or perforated in the manner customary with jacquards so that when moved into engagement with the aforesaid pins 13, certain of the pins pass through the perforations and the plates 7 carrying such pins remain stationary while the remainder of the pins contact with the unperforated part of the card and the plates appertaining to said pins are slidably displaced. This movement transmits through the aforesaid pivoted cranked arms 8 an upward pulling effect upon the cords 10 attached thereto, and the guides 1 to which said displaced cords are attached are raised to a position so as to be unaffected by the rotating cam 5. It will be appreciated, therefore, that those guides which are not raised by the jacquard mechanism are operated by the cam device and aforesaid jacks to lay their threads upon the needles. 90 95 100 105

Each jacquard card carrier 14 is intermittently rotated by any known or approved means such as a clawker member 25 engaging with pins 26 carried by a collar or disc fixed to rotate with said jacquard member. After displacement of the carrier 14 by the clawker 25 a spring 27 encircling one of the sliding rods 22 coacts with a flat disc or plate 28 to retain the jacquard carrier in the required position. 110 115

Each of the depending thread guides is advantageously operated upon by a suitable spring 29 which functions normally to retain the guides in the lowered position and also to pull said guides radially inwards after having been displaced outwards during the laying of the thread. 120

Any suitable number of jacquard mechanisms as before described may be incorporated in the machine, and it is to be understood that the construction and mode of operation of such jacquards can be modified in many ways. 125

In applying the invention to an existing 130

machine, (as is represented in Fig. 2) wherein the ordinary depending thread guides 110, which are not themselves vertically adjustable, extend around the major part of the circumference of the machine, the thread guides are selected by a rotary cam 5a, with a narrow bit, which is adapted for vertical reciprocation at predetermined times, by means of a pattern controlled pivoted lever 54 at the upper part of the machine, so as to engage with or be disconnected from stepped butts 30x, that is, butts 30x at different heights on intervening jacks. In that form of machine wherein the cam acts directly on the thread guides, butts 1b may be formed directly on said guides (as represented in Figure 6); but in Figure 2 the butts 30x are represented as being carried by intervening jacks 1d which are otherwise of ordinary construction and well known in the art. The particular jack 1d shown in Fig. 2 has a full complement of butts and therefore such jack and the thread guide appertinent thereto will be displaced at each revolution of the cam 5a irrespective of its height. Other jacks d' may have only one, or two or a different number of butts provided at predetermined heights accordingly as may be required in the use of the machine. To conveniently provide for both the rotary and the vertical movements of the cam 5a the following mechanism is represented in Fig. 2: the cam is connected with the rotary hollow shaft or spindle 50 by which it is turned, and this shaft or spindle is slotted at 51 to permit vertical movements of the cam, which is connected, by screws or pins 53, with a sleeve or hollow shaft 52 within the shaft 50 and surrounding the stationary shaft or rod 4. The lever mechanism 54 already referred to is connected with the hollow sleeve or shaft 52 as represented. A series of additional jacquard operated vertically movable guides 11a is assembled within the comparatively small space which, in these machines as at present constructed, is unoccupied by thread guides. Referring again to Fig. 2 it will be seen that there are jacks 30 arranged between the rotatable and vertically movable cam 5a and the said additional thread guides 11a, such jacks 30 each having on one side a comparatively long plain butt 30a of uniform height with which the cam 5a engages at each revolution, and on the opposite side of the jack is a butt 30b preferably of curved or inclined formation. The guides 11a are formed each with a cranked or angular portion 11b which, when the guides are in lowered, normal position are disposed so that the curved butt 30b on the jack 30 coacts therewith and, when operated upon by the rotary cam, radially displaces the guide. When, however, a guide 11a is raised by the aforesaid jacquard mechanism the cranked part 11b of the guide is raised above the level of the curved

butt 30b on the jack 30 and no radial movement is transmitted to the guide from the cam 5a. The reciprocation of the cam 5a to effect a fresh selection of the jacks 1d and guides 11a is suitably timed to take place while said cam is in engagement with the plain jacks 30. 70

It will be appreciated that by the employment of jacquard operated guides a very extensive range of patterns can be produced, and in the case of stockings and socks, such pattern can be of a continually differing character along the entire length and/or width or circumference of the leg or article, in fact each and every thread guide can be independently operated. 75 80

Additionally, the changing from one pattern to another can be effected in a very simple and expeditious manner, it being only necessary to remove the jacquard cards and replace same with another or others, no alteration of the thread guides or jacks being necessary. 85

We claim:

1. In a circular knitting machine a plurality of displaceable thread guides, a rotary cam device operating to displace said guides and jacquard mechanism functioning selectively to move said thread guides into a position in which they are unaffected by said cam device. 90 95

2. In a circular knitting machine a circular row of needles, a series of radially movable thread guides, a rotary cam operating successively to displace said guides radially relatively to said needles, jacquard mechanism connected with said guides and functioning to raise them into a position where they are unaffected by said cam, and means operating to return the guides to their normal position after being raised. 100 105

3. In a circular knitting machine a circular row of needles, a circular row of depending thread guides, a rotary cam functioning successively to displace said guides radially and determine whether they are in a feeding or non-feeding position relatively to the needles, jacquard mechanism connected with said guides and operating to raise them clear of the rotary cam and spring means operating independently on each guide to return them to the normal position after being raised. 110 115

4. In a circular knitting machine, a circular row of needles, a circular series of radially displaceable depending thread guides, a rotary cam device functioning successively to move said guides radially so as to determine whether they are in a feeding or non-feeding position, a plurality of jacquard devices each operating to displace selected guides of a separate series or group constituting a part of the circular row of thread guides so as to move said guides to a position wherein same are unaffected by the ro- 120 125 130

- 5 tary cam, means for operating the jacquard devices in succession so as to effect selective displacement of each series or group of guides successively, and means for returning the 5 guides to their normal position after displacement by said jacquards.
- 10 5. In a circular knitting machine, a circular row of depending thread guides capable of radial displacement, a cam operating within said row of guides, said cam being rotated to move selected guides radially to a feeding position, means for imparting axial motion to said cam at predetermined intervals, said axial motion functioning to 15 vary the selection of guides contained in the major portion of the circular row of guides, a jacquard device, said jacquard being connected to the guides contained in the remaining comparatively small section of the circular row of guides and operating to select therefrom guides for radial displacement by the rotary cam, and the axial movement of the cam occurring while the operative part of said cam is passing the jacquard-operated 20 section. 75
- 25 6. In a circular knitting machine, a circular row of depending thread guides capable of radial displacement, a cam operating within said row of guides, a circular row of pivoted jacks located between said cam and guides, the jacks appertaining to the major portion of the circular row of thread guides having stepped butts and the remaining jacks appertaining to a comparatively small 30 section of the row of guides having butts of uniform height, said cam being rotated to move selected guides radially to a feeding position, means for imparting axial motion to said cam at predetermined intervals, said axial motion functioning to vary the selection of 35 guides contained in the major portion of the circular row of guides through the medium of the aforesaid jacks with stepped butts, a jacquard device, said jacquard being connected to the guides contained in the remaining comparatively small section of the circular row of guides and operating to select therefrom guides for radial displacement by the rotary cam through the medium 40 of the aforesaid jacks having butts of uniform height, and the axial movement of the cam occurring while the operative part of said cam is passing the jacquard operated section. 80
- 45 7. In a circular knitting machine a circular row of needles, a circular row of depending thread guides, a rotary cam functioning successively to displace said guides radially and determine whether same are in 50 a feeding or non-feeding position relatively to the needles, jacquard mechanism connected with said guides and operating to raise them clear of the rotary cam, means for returning the guides to the normal position 55 after being raised, a second rotating cam, 85
- 60 8. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 65 after being raised, a second rotating cam, 90
- 70 9. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 75 after being raised, a second rotating cam, 95
- 75 10. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 80 after being raised, a second rotating cam, 90
- 80 11. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 85 after being raised, a second rotating cam, 95
- 85 12. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 90 after being raised, a second rotating cam, 95
- 90 13. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 95 after being raised, a second rotating cam, 100
- 95 14. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 100 after being raised, a second rotating cam, 105
- 100 15. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 105 after being raised, a second rotating cam, 110
- 105 16. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 110 after being raised, a second rotating cam, 115
- 110 17. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 115 after being raised, a second rotating cam, 120
- 115 18. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 120 after being raised, a second rotating cam, 125
- 120 19. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 125 after being raised, a second rotating cam, 130
- 125 20. In a circular knitting machine, a circular row of needles, a circular row of depending thread guides, a rotary cam functioning successively to displace said guides radially and determine whether same are in a feeding or non-feeding position relatively to the needles, jacquard mechanism connected with said guides and operating to raise them clear of the rotary cam, means for returning the guides to the normal position 130 after being raised, a second rotating cam, 135
